ATTORNEY

UNITED STATES PATENT OFFICE

100,584

DESIGN FOR A CENTRIFUGAL DRIER

Anton C. Schmelzer, Cleveland, Ohio

Application June 7, 1935, Serial No. 57,192

Term of patent 14 years

To all whom it may concern:

Be it known that I, Anton C. Schmelzer, a citizen of the United States, residing at Cleveland, in the county of Cuyahoga and State of Ohio, have invented a new, original, and ornamental Design for a Centrifugal Drier, of which the following is a specification, reference being had to the accompanying drawing, forming part thereof.

Figure 1 is a perspective front view of a centrifugal drier, showing my new design, and

Figure 2 is a perspective rear view of the drier shown in Figure 1.

I claim:

The ornamental design for a centrifugal drier, as shown.

ANTON C. SCHMELZER.
